UNITED STATES PATENT OFFICE.

PETER C. HILL, OF WINONA, MINNESOTA.

DESIGN FOR A PHOTOGRAPH HOLDER OR EASEL.

SPECIFICATION forming part of Design No. 31,580, dated October 3, 1899.

Application filed July 15, 1899. Serial No. 724,005. Term of patent 7 years.

To all whom it may concern:

Be it known that I, PETER C. HILL, a citizen of the United States, residing in Winona, in the county of Winona and State of Minnesota, have invented a new and original Design for a Photograph Holder or Easel, of which the following is a specification.

The accompanying drawings, showing my design, contain at Figure 1 an elevation of the design, and at Fig. 2 a vertical cross-section.

The leading feature of the design is the frame for photograph easels or holders, made

in the form of a combined square, calipers, and letter **G**. In the drawings the square is indicated at A, the compass or calipers at B, and the letter **G** at C. The three are combined and intertwined as shown. The surface of the letter is ornamented with foliage.

I claim—

The design for a photograph holder or easel as described and shown.

PETER C. HILL.

In presence of—

LOUIS M. JUNG,
HENRY STERN.
